UNITED STATES PATENT OFFICE.

GEORGE A. COLMAN, OF SEATTLE, WASHINGTON.

INDUCTOR-DYNA MO.

937,675.

Specification of Letters Patent. Patented Oct. 19, 1909.

Application filed December 31, 1908. Serial No. 470,137.

To all whom it may concern:

Be it known that I, GEORGE A. COLMAN, a citizen of the United States, and a resident of Seattle, in the county of King and State of Washington, have invented a new and Improved Inductor-Dynamo, of which the following is a full, clear, and exact description.

My invention relates to dynamos, my more particular purpose being to produce a dynamo of the inductor type having a minimum of wearing parts and without brushes, collectors or commutators.

My invention further relates to the construction of a high-speed rotor having generally the form of a smooth disk made entirely of solid metal, yet heterogeneous as to the magnetic properties.

My invention also comprehends an armature which rotates past a number of stationary conductors so that magnetic lines of force emanating from the rotating armature act upon the stationary conductors, thus setting up currents therein.

My invention further comprehends mounting the rotor upon a comparatively small elastic shaft so as to allow the rotor, when turned at a high speed, to center itself independently of the position of the bearings which support said shaft.

My invention also relates to various improvements in dynamo construction for the purpose of improving the efficiency of the machine.

Reference is to be had to the accompanying drawings forming a part of this specification, in which similar characters of reference indicate corresponding parts in all the figures.

Figure 1 is a substantially central vertical section through my improved inductor dynamo, showing the relative positions of the rotor, the pole pieces upon opposite sides of the same, the field windings for energizing the pole pieces and the shaft and bearings for supporting the rotor; Fig. 2 is a side elevation of the rotor; Fig. 3 is a side elevation of one of the pole pieces removed from the machine, this pole piece having a number of poles of like sign; Fig. 4 is a front elevation of one of the pole pieces and parts rigidly connected therewith; Fig. 5 is a diagram showing one form of wiring suitable for my machine; Fig. 6 is a diagram indi-

cating a slightly different form of wiring for one of the pole pieces.

At 7, 8 are shown the two halves of a casing, these two halves being connected together by aid of flanges 9, 10 and screw bolts 11, so as to form a casing, as indicated in Fig. 1, this casing being provided with feet 12 whereby it is supported. Bolted upon opposite ends of the casing are spiders 13, and these spiders support bearings 14 by aid of webs 14^a which are integral with the spiders. The bearings are covered by housings 15, also integral with the spiders 13. These housings protect the bearings from dust and also serve as oil boxes for lubricating the bearings and shaft. Ventilating holes are shown at 8^a.

At 16 is a very small shaft made preferably of spring steel or other metal, having a fair degree of resilience combined with toughness. Oil rings 17 engage the shaft 16 and depend therefrom, for the purpose of distributing oil upon the shaft at points where it engages the bearings. The shaft 16 is provided with an enlarged portion 18. Shrunken upon this enlarged portion of the shaft is an armature member 19 made of soft steel and provided with sectors 20 integral with it. Disposed intermediate the sectors 20 are other sectors 21 of aluminum. A band 22 of steel is shrunken upon the armature member 19 and the sectors 21, so as to form, together with these parts, a strong and compact wheel made entirely of metal. This wheel constitutes the rotor of my improved generator. It will be noted that this rotor is, as to the presence of metal, at every point merely a continuous disk, but as regards its magnetic properties, it is heretogeneous, being to all intents and purposes a toothed wheel.

At 23, 24 are annular cores which are connected rigidly with the casing by aid of screws 25, as will be understood from Fig. 1. Encircling the annular cores 23, 24 are field windings 26, 27 of annular form connected in series with each other. In effect, the annular cores 23, 24, together with the portion of the casing immediately adjacent to the same, constitute spools for supporting the field windings. The annular cores 23, 24 are provided with flanges 28, 29 to facilitate this purpose, and also to increase the size of the magnetic field.

Mounted upon the flanges 28, 29 by aid of dowel pins 28^a are pole pieces 30, 31. These pole pieces are laminated, being built preferably of thin ribbons of annealed iron or steel wound spirally, different portions of the ribbon being separated by aid of a thin strip of paper. I do not limit myself, however, to any particular style or type of lamination for the pole pieces. When first constructed they are merely laminated annular disks. These are next turned, being thereby rendered concave so as to mate the outer surface of the rotor, as will be understood from Fig. 1. The disks are next each provided with radial slots 32, 33, 34, 35, 36, 37, 37^a, 37^b, and disposed intermediate these are other slots 38, 39, 40, 41, 42, 43, 43^a, 43^b. Both pole pieces are exactly alike as regards their slots.

Windings suitable for a machine are shown in Fig. 5 and are numbered 44, 45, 46, 47, 48, 49, 50, 51, 52, 53, 54, 55, 56, 57, 58, 59. If desired, the windings just mentioned may be connected up in the order stated, or the connections may be changed as desired. For this purpose I provide connectors 59^a, 59^b, 59^c. It may sometimes be desirable to connect these windings in multiple and at other times in series. The windings 59, 44, are connected with terminal wires 60, 60^a. The field windings 26, 27 are excited by a current generated extraneously for this purpose. The winding 56 is connected by a wire 61 and a connector 59^b with the winding 55. A wire 62 and connector 59^a connect the winding 51 with the winding 44. Similarly a wire 63 and connector 59^c connect the winding 47 with the winding 48. As is well known in this art, windings of every kind may be varied considerably in their grouping and in the number of loops of wire used, and also in the size of the wire as well as in the manner in which the windings are connected relatively to each other. I do not limit myself, therefore, to any particular arrangement of the windings relatively to the poles. The various windings 44 to 55, however, are preferably mounted in the order of succession stated. For instance, the winding 44 should be accommodated by the slots 32, 33; the winding 45 by the slots 34, 35; the winding 46 by the slots 36, 37, the winding 47 by the slots 37^a, 37^b. The corresponding windings 48, 49, 50, 51 are made in the opposite side of the machine, after which the windings 52, 53, 54, 55 are made upon the same side of the machine as the windings 44, 45, 46, 47, but in different groups of slots, the four windings last mentioned overlapping the other four windings of the same disk, as will be understood from Fig. 5. Again, if it be desired to produce a single-phase machine, the number of slots is increased and the windings 64, 65, 66, 67 are arranged so as to overlap, as indicated

in Fig. 6, these windings being separated by loops 68, 69, 70. Terminal wires are shown at 71, 72. The faces 73, 74 constitute the poles of the machine. There may very conveniently be sixteen poles upon each side of the rotor. The magnetic lines extend directly across from each pole to the corresponding pole opposite the rotor. The turning of the rotor carries with it the magnetic lines, and as these are carried around they cut the windings, setting up alternating currents.

The dynamo complete contains no brushes, and the only wearing parts about it are the two bearings where engaged by the shaft. As the rotor turns at a very high rate of speed and is neatly balanced, there is little or no vibration. The flexibility and elasticity of the shaft allow the rotor to center itself independently of the supports for the shaft, and also tends to lessen the amount of vibration.

It will be noted that the rotor is, for purposes of convenience in construction, virtually a solid metallic wheel or disk. Yet, for purposes of producing currents in the matter above described, it is, to all intents and purposes, a toothed wheel.

I find that the machine operates well in practice. There is little or no heating in the armature, this being due to the fact that the armature revolves in a perfectly uniform field and cuts no magnetic lines. In other words, the cutting of the lines of force is such that no eddy currents are set up in the armature.

The operation of my device is as follows: The parts being assembled as above indicated, and the machine being excited by aid of a storage battery (not shown) power is applied to the shaft 16, so that the rotor is turned rapidly. Preferably the dynamo is connected directly to a steam turbine of the impact type, and may be run at 14,000 revolutions per minute. The machine develops a very large current of high frequency.

Having thus described my invention, I claim as new and desire to secure by Letters Patent:

1. A rotor comprising a revoluble member of magnetic material provided with sectors integral with it, a plurality of sectors of non-magnetic material disposed intermediate said first-mentioned sectors, and a metallic band encircling all of said sectors for the purpose of holding the same together and forming therewith a solid wheel.

2. In a generator, the combination of field magnets and a rotor disposed adjacent thereto, said rotor consisting of a disk, thick at its middle portion and thin at its edges, portions of said disk being magnetic and other portions of said disk being non-magnetic.

3. The combination of field magnets arranged in pairs and mating each other, said

magnets being provided with inclined faces, and a rotor disposed intermediate said magnets and having generally the form of a disk, said disk being thinner at its outer edges 5 than at points adjacent to its middle, and having portions of its surface substantially parallel with said inclined faces, said disk being of magnetic material and provided with masses of non-magnetic material ex-
10 tending entirely through it.

4. In an induction generator, the combination of a stationary field magnet with laminated annular concave faced pole pieces, facing each other, the pole pieces being radi-
15 ally slotted, to receive the alternating cur-

rent conductors, and a rotor disposed intermediate said pole pieces and having the general form of a disk, being thinner at its outer edge than at its middle, and having its surface parallel with said concave pole 20 pieces, said disk being of magnetic material and provided with masses of non-magnetic material extending entirely through it.

In testimony whereof I have signed my name to this specification in the presence of 25 two subscribing witnesses.

GEORGE A. COLMAN.
